UNITED STATES PATENT OFFICE

GLENN L MOYERS, OF ST. CLAIR SHORES, AND EARL A. ABRAHAM, OF DETROIT,
MICHIGAN, ASSIGNEES TO MONARCH GOVERNOR CO., OF DETROIT, MICHIGAN

GOVERNOR

Application filed December 19, 1927. Serial No. 241,207.

Our invention relates to improvements in governors for use on internal combustion engines in which the governor valve mechanism is actuated by the flow of the fuel charge to the engine and also relates to the governor mechanism disclosed in our application filed September 19, 1927, Serial Number 220,417, although it is not restricted thereto.

10 The objects of our invention are, first, to provide means for determining the profile of a cam that will provide perfect balance between the torque reactions imposed upon the governor valve by the flow of the fuel charge and the counter-balancing means of

15 the governor for any given engine at a pre-determined speed; second, to provide means for establishing the required profile of a governor control cam whose control characteristics change in any increment of movement;

20 and third, to provide means for establishing the required profile of a master governor control cam for a given engine in such manner as to permit of its exact and easy duplication commercially.

25 We attain these objects by the mechanism illustrated in the accompanying drawings, in which—

Figure 1 is a side view of the master governor mechanism assembled to the intake manifold of an engine preparatory to developing its required control cam profile, the valve being shown in the open position; Figure 2, a side view of the master governor mechanism with its control cam profile fully established for a given engine, at a predetermined speed, the valve being shown in the closed position; Figure 3, a view of the master governor mechanism as it appears in a plane parallel to its control mechanism base; and Figure 4, a curve plotted in variables of governor valve opening and torque produced by the said reactions on the valve.

Similar numerals refer to similar parts throughout the several views.

45 In Fig. 1, the lever arm 1 is fastened to the valve shaft 2 by the pin 3. The plate 4 is mounted on the valve housing 5 having flanges 6 and 7. The flange 6 enables the valve housing 5 to be bolted to the flange 8 of the intake manifold 9 of the given in- 50 in Fig. 1. When the test is made with a given engine connected to a dynamometer, the governor throttle is held manually in a position to give the desired maximum speed with no load being registered on the dynamometer. Thereupon the adjusting screw 22 100

ternal combustion engine. The flange 7 enables the valve housing 5 to be bolted to the flange 10 of the carburetor 11.

The valve 12 is suitably fastened to the valve shaft 2. The flexible member 13 is fastened to the lever arm 1 by the screw 14 and contacts with the hub 15 of the lever arm 1 when the valve 12 is in an open position as shown by dotted lines in Fig. 1. The outer end of the flexible member 13 is connected to the spring 16 which in turn is connected to the link 17. The link 17 is adapted to oscillate on the pin 18. The pin 18 is mounted in the plate 4 and allows the link 17 to oscillate in the plane of the movement of the lever arm 1. To provide the necessary clearance for this oscillating movement, the plate 4 has a clearance hole 19. 55 60 65

The above portion of the description of our invention conforms very closely with a like portion of the mechanism disclosed in our application filed Sept. 19, 1927, Serial Number 220,417 and which displayed a control cam. Our present invention discloses a governor mechanism that makes possible the establishment of the necessary profile of the said control cam to secure the proper operation of the counterbalancing means so that the reaction of the said counterbalancing means will be exactly like that of the reactions imposed on the governor valve by the variable forces derived from the operation of a given engine, thus enabling the governor operation to follow the said reactions as developed in any given engine at any predetermined speed. For test purposes to determine the required profile of the control cam, adjusting screws 20 are threaded into the lever arm 1 at spaced positions throughout its length. When thus installed on the governor in connection with the valve 12, the adjusting screws 20 are all backed out of the lever arm 1 so that their upper ends 21 are not touching the flexible member 13, as shown in Fig. 1. When the test is made, with 70 75 80 85 90 95

in Fig. 1. When the test is made with a given engine connected to a dynamometer, the governor throttle is held manually in a position to give the desired maximum speed with no load being registered on the dynamometer. Thereupon the adjusting screw 22 100

is raised until its upper end touches the flexible member 13 and holds the valve 12 in suspension at the desired maximum idling speed with no load. Load may then be applied and the next adjusting screw 23 raised until its upper end contacts with flexible member 13, forcing the valve 12 open sufficiently to maintain the original engine speed with the additional load. This procedure is continued with the remaining adjusting screws, in the lever arm, throughout the entire range of the movement of the valve 12, the application of the load ranging from the maximum idling to the possible full load positions. When this procedure is completed, the adjusting screws will occupy positions as shown in Fig. 2, the upper ends of the adjusting screws 20 forcing the flexible member 13 to the shape as shown in Fig. 2. When this is accomplished the shape of the flexible member 13 will represent the required profile of a control cam that will provide perfect balance between the torque reactions imposed upon the valve 12 and the spring 16 operating through the flexible member 13.

The screw 24 is threaded into the boss 25 on the plate 4 and engages the lever arm 1, thereby forming an adjustable stop for the lever arm 1 and permitting the proper establishment of the open throttle position of the valve 12 in accordance with the maximum fuel demands of the given engine at a predetermined speed.

Fig. 4, is the torque curve of a governor valve in the intake of an engine displaying the reactions exerted on said valve in its different increments of movement. This curve is plotted in variables of throttle opening and intake manifold pressure and is general in resultant form for all internal combustion engines. The abscissæ represent the variables of throttle opening and the ordinates represent the intake passage pressures.

The curve 26 represents the characteristics of the reactive forces necessary to balance a throttle valve at various positions of the valve and the governing forces must be determined with the corresponding reactive characteristics in accordance with the curve 26.

In our invention we are able to produce this proper state of equilibrium between the valve adjustment and the engine load variations in relation to engine manifold pressures, as disclosed in general, in Fig. 4, by our very sensitive and exact counterbalancing mechanism.

We claim:

1. In a valve control mechanism for an internal combustion engine, the combination of a lever connected to the valve and adapted to move therewith, the said lever having a plurality of contact surfaces, a flexible member, connected at one of its ends, to the said lever and resiliently anchored at the other of

its ends, the said flexible member being adapted to contact with the contact surfaces of the said lever, and adjustable means for varying the position of each of the contact surfaces of the said lever relative to the said lever. 70

2. In a governor for internal combustion engines, the combination of a governing member capable of being moved to a closed position by the reactions imposed thereupon by the operation of the engine, a lever connected to the said governing member and adapted to move therewith, the said lever having a plurality of contact surfaces, a flexible member connected, at one of its ends, to the said lever and resiliently anchored at the other of its ends, the said flexible member being adapted to contact with the contact surfaces of the said lever, and means for varying the position of each of the contact surfaces of the said lever relative to the said lever, in 75 80 85 accordance with a predetermined engine speed.

3. In a valve counterbalancing mechanism in a governor for an internal combustion engine, the combination of a lever connected to the valve and adapted to move therewith, a plurality of adjustable members mounted on the said lever, a flexible member connected to the said lever, and a resilient member swivelly anchored, the said resilient member being 90 connected to the said flexible member, and exerting through the said flexible member, a force on the said adjustable members at points increasingly removed from the pivotal point of the said lever during the closing 100 movement of the valve.

4. In a governing device for a hydrocarbon engine, the combination of a housing having an intake conduit, a governing member located in the intake conduit of the said housing, the said governing member being capable of being moved to a closed position by the reactions imposed thereupon by the operation of the engine, a lever connected to the said governing member, adjustable members mounted in the said lever, a resilient member swivelly attached to the said housing, and a flexible member connected to the said resilient member and the said lever, the said flexible member increasing its length of contact with the said adjustable members during the movement of the said governing member to a closed position, thereby causing the said resilient member to exert an increasing tension to maintain the said governing member in a state of equilibrium at a predetermined speed, relative to the reactions imposed thereupon by the operation of the engine. 110 115 120

5. In a governing device having a governing member capable of being moved to a closed position by the reactions imposed thereupon by the operation of the engine, a lever connected to the governing member and adapted to move therewith, adjustable mem- 125 130

bers mounted in the said lever, a resilient member swivelly anchored, and a flexible member adapted to contact with the said adjustable members, the said flexible member having its inner end connected to the said lever and its outer end connected to the said resilient member, the outer end of the said flexible member being increasingly removed from the anchorage point of the said resilient member with the movement of the governing member to a closed position, the said resilient member being thereby rapidly accelerated to a maximum extended position to maintain the said governing member in a state of equilibrium, at a predetermined speed, relative to the reactions imposed thereupon by the operation of the engine.

6. In a governor for a hydrocarbon engine, the combination of a housing with an intake passage, a governing member located in the intake passage of the said housing, the said governing member being supported in the said housing and having an extension through one of the walls thereof, a lever fastened to the extension of the said governing member, adjustable members mounted in the said lever, a flexible member fastened to the said lever, and a resilient member swivelly connected to the said housing, and to the said flexible member, the said resilient member thereby exerting a sufficient reaction on the said adjustable members to maintain the said governing member in a state of equilibrium at a predetermined speed, relative to the reactions imposed thereupon by the operation of the engine.

7. In a governing device for a hydrocarbon engine, the combination of a housing having an intake conduit, a governing member located in the intake of the said housing, the said governing member being capable of being moved to a closed position by the reactions imposed thereupon by the operation of the engine, the said governing member having a shaft extending through the wall of the said housing, a lever mounted on the shaft of the said governing member and adapted to move therewith, adjustable members mounted in the said lever, a resilient member swivelly attached to the said housing, a flexible member connecting the said resilient member and the said lever, the said resilient member causing the said flexible member to progressively contact with the said adjustable members at points increasingly removed from the shaft of the said governing member during its movement to a closed position.

8. In a governor for hydrocarbon engines, the combination of an intake conduit, a governing member located in the said conduit, the said governing member being capable of being moved to a closed position by the operation of the engine, and means for maintaining the said governing member in a state of equilibrium at a predetermined speed, rela-

tive to the reactions imposed on the said governing member by the operation of the engine, the said means comprising a lever connected to the said governing member, adjustable members in the said lever, a flexible member connected to the said lever, and means for maintaining the said flexible member in contact with the said adjustable members in the said lever.

9. In a governor for a hydrocarbon engine, the combination of an intake conduit, a governing member located in the said conduit, the said governing member being capable of being moved to a closed position by the reactions imposed thereupon by the operation of the engine, and means for maintaining the said governing member in a state of equilibrium at a predetermined speed, relative to the reactions imposed thereupon by the operation of the engine, the said means comprising a lever connected to the said governing member and adapted to move therewith, adjustable members mounted in the said lever, a flexible member connected at one of its ends, to the said lever, the said flexible member lying in the path of the movement of the said adjustable members, and a resilient member fastened, at one of its ends, to the said flexible member, the said resilient member being suitably anchored at the other of its ends.

10. In a governor for the intake of hydrocarbon engines, the combination of a housing having an intake conduit, a governing member in the intake conduit of the said housing, the said governing member being capable of being moved to a closed position by the reactions imposed thereupon by the operation of the engine, and means for maintaining the said governing member in a position corresponding to a predetermined engine speed, the said means comprising a lever attached to the said governing member and adapted to move therewith, adjustable means mounted on the said lever, a follower attached to the said lever and resiliently connected to the said housing, the said follower being adapted to progressively contact with the said adjustable means.

11. In a valve counterbalancing mechanism in a governor for an internal combustion engine, the combination of a lever connected to the valve and adapted to move therewith, a plurality of adjusting members mounted on the said lever, a resilient member swivelly mounted, and a flexible member connected to the said lever and the said resilient member, the said flexible member being adapted to progressively contact with the said adjustable members, the said flexible member thereby exerting on the said lever, a reaction whose control characteristics change with every increment of movement of the said lever.

12. In a valve counterbalancing mechanism in a governor for an internal combustion en-

- gine, the combination of a lever connected to the valve and adapted to move therewith, a plurality of adjusting members mounted in the said lever, a flexible member connected to the said lever and adapted to contact with the said adjusting members, and a spring swivelly anchored, the said spring being connected to the said flexible member and exerting progressively, through the said flexible member, a force on the said adjusting means at points increasingly removed from the pivotal point of the said valve of the governor during the closing movement of the valve.
13. In a governing device for an internal combustion engine, the combination of an intake conduit, a valve therein having a spindle, a lever secured to the spindle of the said valve, and adapted to move therewith, adjustable members on the said lever, yielding means swivelly anchored, and a flexible member connected to the said yielding means and the said lever, the said flexible member transmitting controlling forces from the said yielding means to the said adjustable members, at points increasingly removed from the spindle of the said valve during the closing movement of the said valve.
14. In a valve counterbalancing mechanism in a governor for an internal combustion engine the combination of a lever connected to the valve and adapted to oscillate therewith, adjustable members mounted on the said lever, a flexible member connected to the said lever and adapted to contact with the said adjustable members, and resilient means swivelly anchored to permit movement in a plane parallel to the plane of the movement of the said lever, the said resilient means being connected to the said flexible member and thereby exerting an accelerating force on the said adjustable members, during the closing movement of the valve, in accordance with the reactions exerted on the valve by the operation of the engine.
15. In a governing device for an internal combustion engine, an intake conduit, a valve located in the said intake conduit, the said valve being capable of being moved to a closed position by the reactions imposed thereupon by the operation of the engine, a lever connected to the said valve and adapted to move therewith, adjustable members mounted in the said lever, a resilient member swivelly anchored, an intermediate member connecting the said resilient member and the said lever, the said intermediate member progressively conforming to the adjustable members of the said lever during its movement, and means for stopping the said lever in accordance with a predetermined open position of the said valve.
16. In a governing device for an internal combustion engine, an intake conduit, a valve located in the said conduit, the said valve being capable of being moved to a closed po-

sition by the reactions imposed thereupon by the operation of the engine, a lever connected to the said valve and adapted to move therewith, adjustable members mounted in the said lever, a follower adapted to flexibly contact with the ends of the said adjustable members, and means for exerting, through the said follower, variable forces on the said lever, in accordance with the reactions exerted on the said valve by the operation of the engine.

17. In a governing device for an internal combustion engine, a valve capable of being moved to a closed position by the reactions imposed thereupon by the operation of the engine, resilient means opposing the movement of the said valve and connecting means between the said resilient means and the said valve, the said connecting means including a movable lever, adjustable members mounted in the said lever, and a flexible member contacting with the said adjustable members.

18. In a valve control mechanism for an internal combustion engine, the combination of a lever connected to the valve and adapted to move therewith, the said lever having a plurality of contact surfaces, and a flexible member connected at one of its ends to the said lever and suitably anchored at the other of its ends, the said flexible member being adapted to progressively contact with the contact surfaces of the said lever.

19. In a valve control mechanism for an internal combustion engine, a lever connected to the valve and adapted to move therewith, the said lever having a plurality of contact surfaces capable of being adjusted to a definite contour relative to the predetermined speed of a given engine.
